CLAIM

The ornamental design for a compact having mirror for sight impaired users, as shown and described.

DESCRIPTION

FIG. 1 is a perspective view of a compact having mirror for sight impaired users showing my new design;
FIG. 2 is a front elevational view thereof;
FIG. 3 is a rear elevational view thereof;
FIG. 4 is a side elevational view thereof, the side opposite being a mirror image of the side shown;
FIG. 5 is a top plan view thereof;
FIG. 6 is a bottom view thereof; and,
FIG. 7 is a perspective shown in a closed condition.

FIG. 1.

FIG. 4.

FIG. 2.

FIG. 5.

FIG. 3.

FIG. 6

FIG. 7.
